HEAT TRANSFER APPARATUS

Henry J. De N. McCollum, Chicago, Ill.; Thelma McCollum executrix of said Henry J. De N. McCollum, deceased

Application August 15, 1942, Serial No. 454,915

1 Claim. (Cl. 60—31)

My invention relates generally to heat transfer apparatus.

The problem of providing efficient heat transfer from one fluid medium to another arises in the construction of a great variety of heating, ventilating, and similar equipment, but it presents particular difficulties when one of the fluids consists of hot exhaust gases discharged from an internal combustion engine. For example, many attempts have been made to provide some means for preventing the production of a flame in the atmosphere at the outlet of the exhaust stacks of aircraft engines, particularly on military aircraft. These exhaust gases ordinarily discharge to the atmosphere at a temperature between 1400° F. and 1500° F., and, since, especially when the engine is operating at high power output, the exhaust gases contain large amounts of unconsumed vaporized gasoline, the production of a torch-like flame at the outlet ends of the exhaust stacks cannot be avoided. Admixture of the atmospheric air with the exhaust gases while they are flowing through the stack merely results in further combustion and thus increases the temperature of the exhaust gases. The usual method of arresting flames, as by passing the combustible gases through a wire mesh or wire gauze (as employed in the conventional miner's safety lamp) cannot feasibly be used in aircraft exhaust stacks because any such structure placed in an exhaust stack would practically instantaneously be heated to such a high temperature that it would become ineffective as a flame arrester.

In order to be effective, a flame arrester operating on this principle would have to dissipate a large proportion of the waste heat of the exhaust gases, and, since between 3,000,000 and 3,500,000 B. t. u. per hour are passed to the atmosphere with the exhaust gases as waste heat from a 1000 hp. engine, it will be apparent that an extremely large and heavy conventional type of heat exchanger would be required in order to reduce the temperature of the exhaust gases below their ignition temperature.

As distinguished from conventional types of heat exchangers in which the heat is transferred from one fluid to another by conduction through a wall separating the two fluids, the heat transfer apparatus of my invention operates upon the principle of physically conveying the heat energy from one of the fluid mediums to the other. By utilizing this principle, apparatus may readily be constructed which is capable of transferring heat from one fluid medium to another at an extremely high rate without requiring that the apparatus be heavy or bulky.

It is thus an object of my invention to provide an improved apparatus for the rapid transfer of heat from one fluid medium to another.

A further object is to provide an improved means for preventing the burning of the exhaust gases from an internal combustion engine as they are discharged into the atmosphere.

A further object is to provide an improved system and apparatus for heating the cabins of airplanes and the like, utilizing the engine exhaust gases as a source of heat.

A further object is to provide an improved heat exchanger of high heat transfer capacity which is simple in construction, and light in weight.

A further object is to provide an improved apparatus for utilizing the heat contained in the exhaust gases of an internal combustion engine.

A further object is to provide an improved apparatus for the purpose of the elimination of flames at the outlet ends of the exhaust stacks, and for providing heat for the heating of the cabin, for heating surfaces to prevent icing, and for other uses.

A further object is to provide an improved apparatus for transferring heat from a gaseous fluid containing noxious gases to air for heating and ventilating purposes, in which the possibility of escape of the noxious gases to the ventilating air is avoided.

Other objects will appear from the following description, reference being had to the accompanying drawings, in which:

Fig. 1 is a somewhat diagrammatic longitudinal sectional view of one form of the heat transfer apparatus;

Fig. 2 is a transverse sectional view thereof taken on the line 2—2 of Fig. 1;

Fig. 3 is a somewhat diagrammatic longitudinal sectional view of the improved heat transfer apparatus incorporated in the exhaust stack of an airplane for the prevention of flame combustion of the exhaust gases as they emerge into the atmosphere;

Fig. 4 is a transverse sectional view taken on the line 4—4 of Fig. 3;

Fig. 5 is a transverse sectional view of a modified form of the invention in which the heat transfer apparatus is motor-driven;

Fig. 6 is a transverse sectional view of a modified form of heat transfer apparatus;

Fig. 7 is a longitudinal sectional view thereof taken on the line 7—7 of Fig. 6;

Fig. 8 is a plan view of a modified form of the invention; and,

Fig. 9 is a side elevation of the form of the

invention shown in Fig. 8, portions thereof being shown in fragmentary section.

Referring to Figs. 1 and 2, the invention is illustrated as embodied in an apparatus for transferring heat from the exhaust gases of an internal combustion engine to a stream of air to be heated. In this figure, the exhaust gases flow through a generally rectangular conduit 10 in the direction indicated by the arrows, while the air to be heated flows through a similar conduit 12. These conduits are spaced apart, and mounted for rotation between them is a rotary heat transfer member comprising a plurality of discs 14 secured to a drum 16. The drum 16 is carried by a shaft 18 mounted for rotation in a pair of anti-friction bearings 20 carried by suitable supporting members 22. The discs 14 project through thin slots 24 formed in the conduit 10 and through similar slots 26 formed in the conduit 12. These slots are of length corresponding to the chords at which the inner wall surfaces of the conduits 10 and 12 intersect the circular discs, and are made as narrow as possible, while permitting free rotation of the discs 14 through the slots. This clearance between the edges of the slots and the discs is made as small as possible, since these clearances form paths for the escape of gases of combustion from the conduit 10 and for escape of air from the conduit 12. The discs are preferably made of metal, and for the example illustrated, where the discs project into a conduit containing products of combustion from an internal combustion engine, they are preferably of a metal which is not corroded by such gases, such as stainless steel. These discs 14 are made as thin as is compatible with their maintaining their flat shape. It will be noted, however, in this respect, that the discs may rotate at a fairly high speed so that the centrifugal forces acting on the discs will tend to keep them flat.

In operation, the heat transfer apparatus of Figs. 1 and 2, will be effective to transfer a large proportion of the heat from the exhaust gases flowing through the conduit 10 to the air flowing through the ventilating air conduit 12. The space between the conduits is preferably in the slip stream of the airplane so that any leakage of exhaust gases through the slots 24 cannot possibly enter the slots 26 and the conduit 12. As further assurance against such leakage of gases of combustion into the conduit 12, the air flowing in the latter is preferably maintained at a pressure above that in the space between the two conduits so that any leakage will be outwardly from the conduit 12 rather than in the reverse direction.

As the exhaust gases flowing in the conduit 10 pass the portions of the discs 14 which project into this conduit, they will radiate and conduct heat to these portions of the discs. In addition, the flowing gases will, due to friction, cause the discs 14, drum 16, and shaft 18, to rotate in the bearings 20. Such rotation will normally be at such velocity that the lineal speed of the periphery of each of the discs 14 will be somewhat less than that of the speed of the exhaust gases, with the result that there will be some scouring action of the exhaust gases against the surfaces of the discs, thereby to improve the rate of heat transfer from the exhaust gases to the discs. As the heated portions of the discs pass from the conduit 10 through the slots 24, their surfaces will be scoured by the flow of the atmospheric air of the slip stream of the plane in the space

between the conduits 10 and 12 (or by other gaseous flow between them), and any molecular film of noxious gases which might adhere to the disc is scrubbed therefrom. The heated portion 5 of the disc in thus passing through the space between the conduits 10 and 12 will lose some of its heat, but it will still be at a relatively high temperature as it enters the conduit 12, where it will impart a large proportion of its heat to the air flowing through this conduit. There is preferably some difference in lineal speed between the air flowing through the conduit 12 and the peripheries of the discs 14 so that there will be a high coefficient of heat transfer between the discs 10 and such air. In passing from the conduit 12 to the conduit 10, each incremental portion of the discs 14 is further cooled by the air flowing in the space between the conduits so that as each incremental portion of a disc enters the conduit 10, it will be at a relatively low temperature.

The apparatus is preferably so designed that the discs 14 will rotate at a speed such that as each incremental portion leaves the conduit 10 it will be at a temperature which is the arithmetical mean between the temperature of the exhaust gases approaching the discs 14 and the temperature of the air approaching these discs. In any event, the discs 14 should rotate at such speed that there is considerable relative motion 25 between the surfaces of these discs and the gases flowing in the conduits 10 and 12. If the effect of the friction of the exhaust gases upon the surfaces of the discs 14 is, as above indicated, relied upon to cause rotation of the discs, they will necessarily lag behind the combustion gases and provide such relative motion.

Assuming that the exhaust gases approaching the rotating discs are at a temperature of 1500° F., and that the air in the conduit 12 approaching the discs 14 is at a temperature of -10° F., the incremental portions of the discs 14 as they leave the conduit 10, should be at a temperature of 755° F., which, assuming a hundred per cent efficiency of transfer of heat from the exhaust gases to the discs, would mean that the exhaust gases would leave the discs at the same temperature of 755° F. The transfer of heat from the exhaust gases to the discs, while not one hundred per cent efficient, is so efficient that 45 these exhaust gases are reduced considerably below the temperature at which the fuel vapor contained therein will ignite when the exhaust gases are projected into the atmosphere. Therefore, any flame within the conduit 10 is extinguished as the products of combustion flow past the discs 14, and the possibility of reignition is eliminated, and as a result, it is impossible for a flame to be produced at the end of the exhaust stack.

60 This type of heat transferring apparatus may be used for conveying heat from one fluid to another in a large variety of different systems, for example, one of the fluids (i. e., that flowing through the conduit 12) may be a liquid, such as 65 mercury, which does not wet the discs 14. To accommodate the apparatus for use with different fluids, the discs may be made of substantially any material which is capable of retaining heat. For example, the discs may be made of glass, porcelain, various plastic materials, or alloys, depending upon the nature of the fluids to and from which heat is to be transferred, and depending upon the temperature ranges of the fluids, and their difference in temperature, because in this type of apparatus, it is not es-

ential that the material be a good conductor of heat, but rather that it have a reasonably high specific heat and be a good radiator of heat. In some instances, it may be desirable to provide the discs with a surface finish to improve the ability of the surface to receive and emit radiant heat.

In installing the apparatus of Figs. 1 and 2 upon an airplane, the conduit 12 may be located within the fuselage of the plane, while the conduit 10 may comprise the exhaust stack and be located externally of the fuselage and spaced some distance therefrom so that some of the air of the slip stream will flow past the discs 14 to scour any gaseous impurities from the surfaces of these discs as the incremental portions emerge from the conduit 10. As previously indicated, when the conduit 12 is utilized for supplying ventilating air, it is preferably under sufficient pressure at the slots 26 that leakage will be outwardly from the conduit rather than in the reverse direction.

The invention as illustrated in Fig. 3 is utilized for the purpose of cooling the exhaust gases in the exhaust stack of an airplane. In this embodiment of the invention, the exhaust gases flow through a manifold passageway 30 to the rotor 32 of a turbo-supercharger, the bearings and casting of this supercharger being cooled by atmospheric air admitted through a small air ram pipe 34. The turbo-supercharger is merely diagrammatically illustrated and may be of any usual construction which utilizes the kinetic energy of the products of combustion to provide power for driving the engine supercharger or for other purposes. The exhaust gases are discharged from the supercharger through a conduit 36, which is preferably generally rectangular in cross sectional area and has slots 38 formed therein to receive a plurality of discs suitably mounted upon hubs 42 non-rotatably secured to a shaft 44. The shaft 44 is mounted for free rotation in anti-friction bearings 46. The exhaust gases thus flow between the upper portions of the discs 40 which extend within the conduit 36 and are discharged to the atmosphere through an outlet 48. It will be noted that substantially half of each of the discs lies within the conduit 36, whereas, the remaining portion of each of these discs is within the slip stream. Even though the major portion of each of the discs lies in the slip stream, the discs will usually rotate clockwise, that is, against the air stream and with the exhaust gases because of the greater velocity of the latter. However, under low speed cruising conditions, the rate of exhaust gas flow may be sufficiently low that the slip stream will drive the discs 40 in the opposite direction. However, under the latter conditions, the cooling of the gases is of minor importance, and whether or not the discs 40 are rotating at their desired relatively high speed is comparatively immaterial.

Since the effective cross-sectional area of the exhaust stack 36 in line with the vertical diameter (Fig. 3) of the discs 40, may be made substantially as great as that of the remainder of the stack, there will be no substantial increase in back pressure due to the use of the invention. In fact, since the exhaust gases are cooled by the discs 40, their volume is reduced and as a result, the back pressure may be reduced instead of increased.

In such instances as it is not feasible to use the energy of the fluids flowing through the con-

duits as a means for rotating the heat transfer discs, a construction such as shown in Fig. 5 may be employed. In this embodiment of the invention, the parts may be constructed in the same manner as shown in Figs. 1 and 2. Parts shown in Fig. 5 which may be identical with those disclosed and described with reference to Figs. 1 and 2, have therefore had corresponding reference characters applied thereto. The shaft 18 is coupled to a motor 50, which may be supplied with electrical energy from any suitable source, the motor being supported by a pair of brackets 52 connected respectively with the conduits 10 and 12 so as to maintain the discs 14 properly positioned within the slots 24 and 26. The apparatus of Fig. 5 may thus be used when the rate of fluid flow through the conduits 12 and 10 is not sufficiently rapid to cause rotation of the discs, or when the rates of fluid flow through the conduits 10 and 12 must be at substantially the same rate and in the same direction.

This construction is also of utility when an exact temperature control is desired. While the motor 50 will normally be a constant speed motor, it may be a variable speed motor whenever temperature control of the fluid flow through one or the other of the conduits is desired, since the rate of heat transfer will in general and within limits, be dependent upon the speed of rotation of the discs. Thus, by varying the speed of the motor, the temperature of one or the other of the fluids may be controlled, and such control may be effected by suitable thermostatic means whenever required.

When the fluid flow through the conduits is at such low velocity as not to be readily capable of rotating discs such as 14 due to the frictional drag, and particularly when it is not essential to transfer an extremely large quantity of heat from one fluid to the other, a construction such as shown in Figs. 6 and 7 may be employed. In this embodiment of the invention, one of the fluids flows through a ring-sector-shaped conduit 60, while the other fluid flows through a similarly shaped conduit 62, the flow through these conduits preferably being in the same direction, especially if the fluids are flowing at approximately the same velocity. The heat exchanger comprises a rotor mounted upon a shaft 64, a hub portion 66, spokes 67, rim 68, and fan 70. The shaft 64 is mounted in suitable anti-friction bearings 72 for free rotation. The blades 70 are adapted to pass through a slot 76 formed in the conduit 60 and a slot 78 formed in the conduit 62.

Assuming that the rotor is rotating clockwise (Fig. 6), the amount of heat transferred from the fluid flowing in conduit 60 to the fluid flowing in conduit 62 depends not only upon the speed of rotation of the rotor, but also upon the angular propinquity of conduits 60 and 62, as well as the temperature of the air or other medium between the conduits 60 and 62. Because of the relatively large slots which are required in the conduits 60 and 62, the fan-shaped blades 70 will carry a considerable portion of air into these conduits and a considerable portion of the fluid flowing through these conduits to the atmosphere. This type of heat transfer apparatus is therefore of the most utility where the fluids flowing in the conduits are air or other gases whose escape and dilution is of no importance.

A simple modification of the invention shown in Figs. 8 and 9 comprises a foraminous disc 80, illustrated as a screen, mounted upon a spindle 82

rotating in suitably supported anti-friction bearings 83. Fluid to be cooled is directed toward the disc 80 through a conduit 84, the end of which is conformed as indicated in Fig. 9 to tend to force the fluid through the openings in the disc 80. Air to be heated is forced under some pressure through a conduit 86, the end of which is beveled to conform to the plane of the disc 80. Air flowing from the conduit 86, after passing through the disc 80, enters a continuation 87 of the conduit 86, the conduit 87 leading to a place at which the heated air is to be utilized. The kinetic energy of the gases discharged from the conduit 84, which may be the exhaust stack of an internal combustion engine, strikes the foraminous disc 80 at an angle so as to cause the latter to rotate. As each incremental section of the foraminous disc 80 is heated by the exhaust gases, it moves to the space between the conduit sections 86 and 87 so as to heat the air flowing from the former to the latter. The disc 80 may be a screen or a perforated metal disc. The screen will be effective to pick up heat from the exhaust gases more rapidly than the perforated plate because of the greater surface area of metal exposed to the exhaust gases by the wires of which the screen is woven. However, the screen is more fragile than the perforated disc, and if the screen is made of a metal which is even slightly corrodible by the exhaust gases, the screen will, of course, be less durable than a perforated disc.

The underlying principle of operation of the apparatus of Figs. 8 and 9, is essentially the same as that of the previously described embodiments, namely, that a body absorbs heat in moving through the path of flow of a hot fluid and gives up its heat in moving through the path of flow

of another body of fluid, with the possibility that the body may be cleansed of any adhering gas by passing through a third fluid medium intermediate its movement through the other two mediums.

5 While I have shown and described certain illustrative embodiments of my invention, and such showing has been in somewhat diagrammatic form, it will be apparent to those skilled in the art that the invention may be embodied 10 in a wide variety of different types of apparatus in which it is desired to raise or lower, or both, the temperature of one or more fluids. I therefore do not wish my invention to be limited to the illustrative forms of the invention shown, 15 but desire to include within the scope of the following claim all such variations and modifications by which substantially the results of my invention may be obtained through the use of substantially the same or equivalent means.

20 I claim:

For use in an airplane powered by an internal combustion engine and having an exhaust stack for the discharge of exhaust gases from the engine to the atmosphere, means for lowering the 25 temperature of the exhaust gases below their ignition temperature comprising, a foraminous disc mounted for rotation in a plane at an angle to the direction of flow of the exhaust gases and driven at high speed by the exhaust gases in the 30 manner of a turbine, incremental portions of said member alternately moving into the path of flow of the exhaust gases and into the path of cool air, whereby the production of a visible flame at the outlet end of said exhaust stack is prevented.

HENRY J. DE N. MCCOLLUM.
